G. H. DESROCHERS.
PLASTER OF PARIS CUTTER.
APPLICATION FILED MAR. 2, 1920.

Patented Feb. 15, 1921.

WITNESS:

George E. Desrochers
Charles H. O'Donnell

INVENTOR:

George H. Desrochers,
BY Albert M. Moore,
His ATTORNEY.

UNITED STATES PATENT OFFICE.

GEORGE H. DESROCHERS, OF LOWELL, MASSACHUSETTS.

PLASTER-OF-PARIS CUTTER.

1,368,244.

Specification of Letters Patent. Patented Feb. 15, 1921.

Application filed March 2, 1920. Serial No. 362,671.

To all whom it may concern:

Be it known that I, GEORGE H. DESROCHERS, a citizen of the United States, residing at Lowell, in the county of Middlesex and Commonwealth of Massachusetts, have invented a certain new and useful Improvement in Plaster-of-Paris Cutters, of which the following is a specification.

This invention relates principally to 10 plaster of Paris cutters or shears adapted to cut and break the plaster casts or jackets in which surgeons and physicians secure broken and dislocated limbs or displaced parts after setting the same. Said invention is applicable, however, to other hand 15 operated cutters and shears requiring great power.

Such casts and jackets are made of plaster of Paris laid over an inner bandage of 20 fibrous or textile material, as cotton wadding, and being applied in a plastic condition become very hard and require for removal the use of metallic instruments and considerable muscular force, and frequently 25 a previous softening of the cast by the use of vinegar or acid.

The instruments most commonly used for 30 removing the plaster are knives, as jack-knives, or shoemakers' knives, which are drawn over the plaster to form grooves or 35 scores by means of which the plaster may be more easily broken. Sometimes a "can-opener" is used for removal of the plaster. Of course, the patient is liable to be cut in the operation, which sometimes lasts for 40 hours and fatigues the operator and the patient and is expensive for the patient.

The object of this invention is to increase 45 the efficiency of the applied force and save time of the surgeon, and to avoid injury, expense and fatigue to the patient, and the use of vinegar or acid.

In the accompanying drawings, Figure 1, is a side elevation of a plaster of Paris cutter 50 embodying my invention, the end-portion of the handles proper being broken away; and the jaws being closed; Fig. 2, a cross-section of the base handle, showing the joint which connects said handle to the operating lever; Fig. 3, a cross-section of the 55 sliding fulcrum on the line 3-3 in Fig. 1; Fig. 4, a side elevation of the cutter open.

A indicates the base handle or lever which in actual cutting is stationary, but is used

to crowd the cutters forward for a new cut. 55 Integral with the handle A or rigidly secured thereto is the upper stationary female cutter a^4 , having an upwardly flaring opening to receive the lower movable male cutter E and prevent lateral movement of the 60 same.

The cutter E is guided partly by a pin e^1 passing through the sides of the cutter a^4 and through a slot e in said cutter E, and partly by its connection with the intermediate lever C.

The cutter E is provided with an upwardly extending arm e^2 the upper end of which is jointed or pivoted at e to a short arm e^1 of the intermediate lever C which 70 is fulcrumed at a^2 on the base handle A.

The slot e in the movable cutter E is preferably so arranged as shown in Fig. 4, and the path of the pivot e is such that the angle between the straight cutting surfaces of 75 the cutters will be substantially constant, to permit of continuous shearing. The lower end of said slot also acts as a stop to prevent the movable cutter from entering the stationary cutter farther than necessary. 80

One of the cutters, preferably the stationary cutter a^4 is provided with notches a^5 on the surface which contacts with the work to prevent the cutters from slipping off the 85 cast while shearing.

The free end of the intermediate lever C is jointed to a sleeve or slide D which surrounds and moves freely on the operating lever or handle B.

Said slide D is provided with trunnions d^1 d^2 which turn freely in plates d^2 d^2 rigidly secured to the free end of the intermediate lever C and extending below said lever C. Said slide D, as the cutters are closed, approaches the fulcrum a^2 of the 95 operating lever and gives an increasing leverage to the latter with the same exertion of force, thus relieving the surgeon or operator.

The plates d^2 d^2 on opposite sides of the 100 sleeve or slide prevent twisting of the cutters on each other.

When the handles a b proper or free ends of the handles A B are brought together, the cutter E is drawn up into the cutter a^4 as 105 shown in Fig. 1, cutting or punching a narrow strip out of whatever is between the cutters or jaws and allowing the cutter or

jaw E to be pushed forward into the slit thus formed in order that cutting may be continued.

I claim as my invention:

- 5 1. A plaster of Paris cutter having in combination a base-handle, a female cutter rigidly secured to said base-handle, a male cutter arranged and guided in said female cutter an intermediate lever fulcrumed on
- 10 said base-handle and jointed to said male cutter, an operating handle fulcrumed on said base-handle, a sleeve sliding on said operating handle, and jointed to the free end of the intermediate lever.
- 15 2. A plaster of Paris cutter having in combination a base-handle, a female cutter rigidly secured to said base-handle, a male cutter arranged and guided in said female cutter an intermediate lever fulcrumed on
- 20 said base-handle and jointed to said male cutter, an operating handle fulcrumed on said base-handle, a sleeve sliding on said operating handle, and a link connecting the free end of said intermediate lever and said
- 25 sleeve.
3. A plaster of Paris cutter having in combination a base-handle, a female cutter rigidly secured to said base-handle, a male cutter arranged and guided in said female
- 30 cutter an intermediate lever fulcrumed on said base-handle and jointed to said male

cutter, an operating handle fulcrumed on said base-handle, a sleeve sliding on said operating handle, said sleeve having trunnions and plates secured to the free-end of 35 said intermediate lever and having openings to receive said trunnions.

4. A plaster of Paris cutter having in combination a base-handle, a female cutter rigidly secured to said base-handle, a male 40 cutter arranged and guided in said female cutter an intermediate lever fulcrumed on said base-handle and jointed to said male cutter, an operating handle fulcrumed on said base-handle, a sleeve sliding on said 45 operating handle, means of forcing said cutters into operation, one of said cutters having notches to engage the work and to prevent slipping thereon.

5. A plaster of Paris cutter having in 50 combination a base-handle, a female cutter rigidly secured to said base-handle, a male cutter arranged and guided in said female cutter an intermediate lever fulcrumed on said base-handle and jointed to said male 55 cutter, an operating handle fulcrumed on said base-handle, a sleeve sliding on said operating handle, means for forcing said cutters into operation, said female cutters having notches to engage the work and to 60 prevent slipping thereon.

GEORGE H. DESROCHERS.
